[57] CLAIM

I claim the ornamental design for a smoking device, as shown and described.

DESCRIPTION

FIG. 1 is a perspective view of the novelty smoking device. FIG. 2 is an elevational view of the rear of the smoking device.

FIG. 3 is a right side elevational view of the smoking device. FIG. 4 is a left side elevational view of the smoking device. FIG. 5 is a view of the bottom of the smoking device; and, FIG. 6 is a view of the top of the smoking device.

The broken lines are shown for illustrative purposes only and form no part of the claimed design.

The surface(s) or portion(s) of the article not shown in the drawing or described in the specification form(s) all no part of the claimed design.
